UNITED STATES PATENT OFFICE.

FREDERICK WILLIAMS, OF SOMERVILLE, MASSACHUSETTS, ASSIGNOR TO ACME REGISTER COMPANY, OF SOMERVILLE, MASSACHUSETTS, A CORPORATION OF MASSACHUSETTS.

STATION-BOX FOR WATCHMEN AND FIRE-ALARM SIGNALING.

1,167,961.

Specification of Letters Patent. Patented Jan. 11, 1916.

Application filed September 18, 1912. Serial No. 720,922.

To all whom it may concern:

Be it known that I, FREDERICK WILLIAMS, of Somerville, in the county of Suffolk and State of Massachusetts, a citizen of the United States, have invented a new and useful Improvement in Station-Boxes for Watchmen and Fire-Alarm Signaling, of which the following is a specification.

This invention is an improvement upon the signaling system invented by me and patented December 1, 1914, No. 1,119,738. It will therefore be seen that this apparatus is related to the prior invention and is to be regarded in connection therewith.

15 My invention relates to that class of apparatus in which the recording boxes or stations are located in various parts of a building or other place to be protected. The apparatus in the first station is electrically controlled from the central station and each successive station is electrically controlled from the previous station in sequence, for my system contemplates a predetermined tour of duty on the part of the watchman and a verification of his faithfulness by a record dependent not only upon an act on the part of the watchman at certain specific times, but from certain specific stations in rotation. In addition each station is connected with a fire alarm office where a record is made automatically and by the one operation on the part of the watchman at the same time that he makes a record at the central station. By means of the same apparatus and connections differently utilized an alarm of fire may be turned in.

30 My invention will be understood from the drawings in which—

Figure 1 is a diagrammatic view showing the apparatus connected according to my system, three local stations being shown together with the central station. Fig. 2 is an elevation of one of the station boxes. Fig. 3 is a section of the box as a whole taken on line 3—3 of Fig. 2, showing only the fire alarm. Fig. 4 is a corresponding section on line 4—4 of Fig. 2. Fig. 5 is a general view showing the central station.

The apparatus is intended for a warehouse, yard, or other locality where a watchman is to make his rounds at specified times and includes the central office and a fire sta-

tion which may be in the central office or at any convenient point.

Referring especially to Fig. 1, A is the central station and A¹ is the fire station. Connected with the central station are three local stations 32, 33, and 34. These stations are identical in construction with the exception of the details of the automatic circuit breaker of the fire alarm circuit which will be described below. B is the battery. C is a clock shown in Fig. 5. From the central station proceed three lines forming part of two circuits, each of which includes the battery B; that is, there is what may be termed the main line D which passes from the circuit breaker d to the battery B and thence as D¹ to the point d¹ where it divides, the portion E¹ going to the last station 34, and the portion F¹ forming part of the fire alarm circuit. E¹ is the connection between the first recording station and the clock mechanism, and F¹ the return of the fire circuit. Each station has an insulated plate f attached to the base K which plate has a series of connecting parts which are numbered from f¹ to f⁷ inclusive to each of which runs the wires from the various parts of the station and to which are connected the various incoming and outgoing wires from the various parts of the system.

I will first describe one of the station boxes, 32, 33, and 34. The various stations are alike except as to their fire alarm, all of which operate in the same way but each of which gives its distinctive signal. In each station the mechanism is mounted on a base K forming the back of the box. The recording mechanism will now be described. Starting with station 32, e is a screw connection from which a wire runs to a post f¹ for connection with the incoming wire E¹ which is thus connected with the circuit breaker e¹. This circuit breaker normally lies against the contact point e² which is connected at the screw e³ by a wire with post f² and the outgoing wire E² of the main circuit which runs to the post f¹ of the next station 33, the parts e² and e³ being integral with each other. e⁴ is an arm against which the circuit breaker is pushed at the proper time by means of the push rod J to be described below. It is connected with post f⁴ from which

wire E^{33} runs to post f^2 of the next box. When contact is made with the arm e^4 circuit is closed through the next box in series as will be below described. This arm has a slight yielding movement against the force of a spring e^5 which holds the arm e^4 normally in place. The push rod J carries a hook J^1 and is mounted to slide in the frame j carried on the base and the bearing j^1 and is surrounded by a spring j^2 , one end of which engages with a portion of said frame, the other end being engaged by a pin j^3 on the push rod so as to maintain the push rod in such a position as to allow the circuit breaker to remain normally closed. The end of the push rod is provided with insulating material and adapted to engage with the circuit breaker e^1 and break the circuit when pushed.

The push rod is normally locked to prevent it from being operated and as shown it is released by means of the armature h operated by the electromagnet H . The electromagnet at this station is in a shunt circuit E^{32} which is temporarily operated in the manner below described. The armature h is pivoted at h^1 and is slotted as indicated at h^2 , a catch h^3 passing down through said slot and adapted to engage under the edge of said slot and hold up the armature from contact with the push rod J when the unlocking of the push rod is desired. Normally, however, the armature is free. The catch h^3 is held in position to ride under the armature when the armature is in its highest position by means of a spring h^4 . The push rod J is also provided with a collar j^4 which normally engages the end of the armature h so that when the armature is in its lowest position as indicated in Fig. 2 the push rod cannot be moved. When, however, the armature has been attracted by the electromagnet H it is caught in this upward position by the catch h^3 as described and is there held so that the push rod may be moved to open the circuit breaker e^1 (see Fig. 2). This act of moving the push rod forward, however, also releases the catch h^3 from its engagement with the armature as a portion of the collar j^4 strikes the catch so that the armature is in position to fall again upon the return of the push rod and relock the push rod. I have indicated the operation of the armature as being controlled by gravity on the one hand and by the magnet on the other, but it is apparent that if the apparatus be laid horizontally the position of the armature may be controlled by a spring instead of gravity. The frame j in which the push rod J is mounted and the other parts of this apparatus are mounted on an insulated base or otherwise insulated from the box containing the mechanism as indicated in Fig. 4. The apparatus as a whole at each station is inclosed in a box

having a base K with a front K^1 having an opening covered by a spring closed door K^2 , by opening which the watchman reaches the hook J^1 to operate the push rod J . A partition K^3 incloses the mechanism within the box and protects it from any tampering on the part of the watchman. This partition K^3 has an opening K^5 through which projects the fire alarm handle F^2 and in front of this handle is an opening in the front K^1 covered with a sheet of mica K^4 which can easily be broken to turn the handle F^2 as below described.

The fire alarm apparatus is shown in the upper part of Fig. 2 and in Fig. 3. It is connected with the watchman's record so that each time the watchman makes a record at the central office from a given box he also makes a record at the fire station which may be and preferably is in a different location from the central office. My system comprises therefore a record at two different offices, one for example, the central office in the building and the other a fire office which may receive fire signals from any number of buildings; the record at the central office shows whether the watchman is doing his duty as a guard and the record at the fire office showing that he is going his rounds as a fire patrol.

L is a shaft supported in a frame comprising the plates M and M' and the posts m , the plate M being attached to the back K of the box. The outer end of this shaft carries a crank F^2 . The shaft also carries a clock spring N , one end of which is attached to the shaft L and the other end to the post n on the plate M' . The shaft L also carries a gear l free to turn thereon except as it is provided with a pawl l^1 which engages a ratchet l^2 fast on the shaft L . When the shaft L is turned one way therefore it turns the gear l , but when it is turned the other way the gear is stationary. The gear l meshes with a pinion p on the shaft P , supported in the plates M M' , so that when the gear l rotates the shaft P will rotate with it. The speed of rotation of the shaft P is controlled by an escapement mechanism Q of any suitable construction operated by the gear p^1 on the shaft P , the pendulum of this escapement being shown at q .

Mounted on the shaft L to turn therewith and insulated therefrom is a wheel R . This wheel comprises a hub carrying three disks r , r^1 and r^2 . The disks r and r^1 are cut away at r^3 or otherwise arranged so that during a portion of the revolution electrical contacts s , s^1 , normally resting upon them and hence being in electrical connection with each other will become disconnected from each other. The third disk r^2 is cut away for the same purpose and serves as a support for contact s^2 which forms a ground connection. These contacts are supported in a

block S of insulating material so as to be insulated from each other and from the box K. The shaft L also carries an arm L¹ provided at its outer end with a friction roll 5 L² which engages the end of a lever L³ pivoted in bearings mounted on the back of the box K, the lower end of this lever lying in the path of the pin j³ on the rod J so that with every forward movement of the 10 rod J the lever L³ will be moved and will give to the shaft L and the parts carried by it a partial rotation against the force of the spring N which will return them to their original position when the rod J is released. 15 The disk r² also carries an insulated block r⁵ which is so located as to press a spring contact t against a similar contact t¹, both of which are supported in a block T of insulating material so as to be insulated from 20 each other and the box K. The shaft P carries a wheel V insulated from it and comprising a hub V¹ with disks v, v¹, v², all notched alike as shown and for the purpose to be described. The disk v² is also cut 25 away for most of its periphery. Contacts w, w¹ and w² supported in the insulated block W rest on the periphery of these disks.

The various contacts forming part of the 30 fire alarm mechanism are connected as follows: The contact s is electrically connected with the contact w. The contact s¹ is connected with the post f⁵ which is connected with the fire circuit F¹. The contact w¹ is 35 connected with the post f⁶ which is also connected with the fire circuit F¹. In the last station 34 in the series the post f⁵ is connected by a return wire F with the battery line D¹. The posts f⁵ and f⁶ are also 40 connected respectively with the contacts t and t¹ which when the apparatus is not working short circuits the fire apparatus but which being separated by any movement of the wheel R then allows the fire 45 alarm to become operative electrically. The contacts s² and w² are connected with the post f⁷ which is connected with the ground through the wire G or other connection.

The apparatus at the central station 50 comprises a watchman's clock of ordinary construction having an arbor Y which is rotated by clock work at a given speed. It carries a paper recording dial Y¹ provided with segmental divisions which may be perforated or indented on the breaking of the 55 main circuit which passes through the electromagnet Y² and the consequent impulse of the marker Y³ on the armature of electromagnet Y² against the dial Y¹ by the 60 action of a spring. This spring is not shown as it is similar to the ordinary retraction spring of an armature to an electro-magnet, but it is preferably somewhat stronger in order to give the marker power 65 to indent the dial. The armature is mount- ed in the usual way and the marker Y³ is mounted on it to move with it. On the arbor Y is also a disk Y⁴ having fingers v which in turn engage and lift the circuit breaker d and cause momentary contact 70 with the arm d³ as below described. The apparatus also includes a recorder Z which is in the fire circuit and which is operated as below described, simultaneously with the Y³ and records the number of the station. 75 A similar recorder Z¹ also in the fire circuit is located at the fire station and makes a similar record there. I prefer to use for this purpose a Morse recorder of ordinary type. All these stations are alike so far 80 as the recording mechanism is concerned so that this description will answer for the description of all the boxes.

I will now describe the operation of my 85 system including the above described signal boxes, 32, 33, and 34. Normally the circuit E, E¹, E², etc., is completed through the series of circuit breakers, one at each station, that is, the wire E¹ runs to the post f¹ and circuit breaker e¹ and the circuit is completed through the contact point e² connected normally at the point e³ with the post f³, the wire E² and the next station, etc., the connection at the last station being with the 90 wire E. The circuit breaker d of the watchman's clock at the central station A is operated by means of the rotating dial Y forming part of the clock, one arm y of which engages and lifts the circuit breaker d of the central station and causes it to make 95 electrical contact with the arm d³ and throw it into circuit through the shunt wire E³². This wire E³² being connected with post f² in station 32 forms what may be termed a local shunt through the electromagnet H, 100 which electromagnet is also connected with the point e³ and post f³ so that the circuit is closed through the wires E² and E as before. This change of circuit throws the 105 battery on the electromagnet H energizing it and thereby lifting its armature h for the moment and unlocking the push rod J at this station, the armature when released dropping on the catch h³ so that it will not interfere with the operation of the rod. The 110 push rod J is then in condition to be operated. The watchman pushes it to the left at the proper time, this action causing its engagement with the circuit breaker e⁴ and breaking the circuit at e³ and hence releasing the armature carrying the marker Y³ and causing the recording apparatus at the 115 central station to make a puncture in the dial sheet as described above. The movement of the push rod J also moves the lever L³ which turns the wheel R approximately $\frac{1}{3}$ of circumference, thus breaking the shunt connection through the contacts t, t¹, and throwing the battery current through the 120 fire alarm circuit. Upon the return of the 125

push rod the spring N causes the wheel R and lever L³ to return to their normal positions and also gives a complete rotation to the wheel V through the engagement of the pawl l¹ with its ratchet l² and the gear connection with the shaft P. By this means the contacts w and w¹ are caused to wipe over the periphery of the wheel V, breaking the circuit as they pass the notches so that they cause the recorders Z and Z¹ to make an appropriate record at the central and fire stations. The notches being differently arranged at each station the record from each station is distinctive. The movement of the push rod against the circuit breaker e¹ also causes it to make contact with the arm e⁴ which functionally corresponds with the arm d of the clock throwing into circuit for the instant the local shunt E³³ of box 33 which is connected with its electromagnet H, thus causing the energizing of the electromagnet H in the box 33, and freeing the push rod therein so that at the proper time the watchman may push the rod and cause the making of a record from box 33, this act also setting box 34 through shunt E³⁴. The record is made from box 33 because in the pushing of the push rod J in that box the circuit at e³ in that box is broken for the instant and hence the current which had been passing from the battery B through the recording instrument A¹, circuit breaker d, wire E¹, circuit breaker e¹ of box 32, wire E², circuit breaker e¹ of box 33, wire E² circuit breaker e¹ of box 34, and wire E and D¹ being at the moment broken, causes the operation of the recording instrument at the central office. It will be seen that this operation may be repeated indefinitely according to the number of boxes in the system. Breaking the last circuit at e³ throws the current temporarily through E. When the watchman has gone his rounds he can do no more until the dial has rotated far enough to bring the next arm v into contact with the circuit breaker d so that the same sequence of operations is gone through again by the watchman. The recording dial Y¹ on the clock shows by the punctures in it the times at which the watchman has made his record and this record is confirmed by the recorders Z, Z¹. This record he can only make by visiting the boxes in a definite order.

The opening in front of the box closed by the mica K⁴ is opposite the crank F² and in case of fire the watchman breaks the mica K⁴ and turns the crank one complete revolution until it strikes the pin l³ projecting from the inside of the wall K³, and then lets go. In this case not only are the shunt contacts t, t¹ allowed to separate and break the shunt circuit but the fire circuit is broken as at r³ for a period representing say $\frac{1}{6}$ th of the rotation of the wheel R during which

time the contacts r, r¹, and r² are electrically disconnected so that the recorders Z, Z¹ indicate a long connected line thus _____. During all this time and until the wheel R stops its rotation the wheel V is constantly rotated, in the form of my invention shown rotating nine times. During its first rotation it can make no record because of the breaking of the circuit while the fingers s, s¹, s², are passing the portion r³ of the periphery of the wheel R. When they again rest on the periphery of the wheel R the circuit is again closed to be broken only as the contacts v, v¹, v² pass over the notches in the wheel V when the signal represented as follows from box 32 is sent is, viz: - - - -, etc. Contacts r² and v² are provided connected with the ground so that in case of any fault on either side of the fire circuit the line will be grounded and the apparatus will still be effective as a fire signal.

In order to make a register at each box of the number of times the box has been used and so have an additional check on the watchman I prefer to connect a counter of ordinary construction to the push rod J. Such a counter is shown at z and in this case it is operated from the lever L³ by means of the crank z¹ which is connected to and operates the lever z² pivoted to the plate z³. A connection z⁴ between this lever z² and an arm on the counter z causes it to make a count with each movement of the lever L³ and push rod J against the force of the spring z⁵.

I have shown two fire signals, one at the central office of the building and one at the fire station. The one at the central office may be a bell or it may be omitted entirely, or the separate fire station may be omitted according to circumstances. For example, in a warehouse or department store system a fire station elsewhere is desirable, but when the property to be protected is a large yard which has its own fire protection the two stations may well be combined in one. The use of a fire and watchman's record at the same central station is very desirable as it enables the manager of the building or property to satisfy himself that the two systems are working satisfactorily. The paper dial on the clock may be divided into fractions of an hour so that a record on it tells the minute at which the record is made by the watchman and a similar mechanism may be used if desired by which to make a record at the fire station.

I do not mean to limit myself to the precise construction of apparatus shown in the drawings and above described because it will occur to one skilled in the art that modifications of the apparatus and circuits may be used to accomplish the desired result, and so far as I know I am the first to make a combined circuit by which stations can

only be operated in a given order and each operation sends two different signals, one of which in a modified form may be sent from the same point to indicate fire or that assistance against burglars is needed.

5 Claims:

1. In a signal system comprising a central station and a series of signal stations, in combination with two recording instruments one giving a time signal and the other a signal which by its character will designate a particular place located at said central station, means located at a signal station adapted to send a time signal and means adapted 10 to send a place signal, means adapted to send said signals simultaneously and means whereby said place signal may be sent independently of said time signal.

2. In a signal system comprising a central station and a series of signal stations, means located at a signal station for sending a place signal and means also located at said signal station operable to indicate that said place signal is a fire or special signal, said 20 place signal comprising a rotary circuit breaker adapted to make and break the circuit at predetermined intervals and said indicating signal comprising a circuit breaker operable during one or more complete rotations of said rotary circuit breaker, in combination with a recording instrument located at said central station, a circuit connected therewith and breakable by said circuit breaker as described.

3. In a signaling system comprising a series of signal boxes each adapted to be operated normally in a closed circuit, means for sending a place record comprising a rotary circuit breaker and means for operating said 30 circuit breaker comprising a spring operated shaft and gear connections between said shaft and said rotary circuit breaker, said shaft carrying a wheel, two pairs of contacts, one pair engaging said rotary circuit breaker and the other said wheel, and two ground contacts, one adapted to be available upon the breaking of any part of the circuit upon one side of the circuit breaker and wheel, and the other to become available upon the breaking of any part of the circuit upon the other side of the circuit breaker and wheel, as described.

4. In a signaling system comprising a series of signal boxes each, means for sending a place signal comprising a rotary circuit breaker and means for operating said circuit breaker comprising a spring operated shaft, said shaft carrying a wheel, two pairs of contacts, one pair engaging said rotary circuit breaker and the other said wheel, whereby a circuit may be made through each pair of contacts, said wheel having an interruption in its periphery whereby the circuit through its pair of contacts is temporarily broken to give a signal independent

of the signal given by said rotary circuit breaker.

5. In a signaling system comprising a series of signal boxes, in combination with a time-recording mechanism as described, a 70 place-recording mechanism adapted to be operable normally in a closed circuit, and means to operate said mechanism substantially as described, and a lever pivoted to engage said place-recording mechanism at 75 one end, said lever also being in engagement with said time-recording mechanism at the other end whereby said signals may be sent simultaneously.

6. In a signaling system comprising a series of signal boxes, in combination, a time-recording mechanism, a place-recording mechanism, connections between said time-recording mechanism and said place-recording mechanism, whereby the operation of 80 said time-recording mechanism will cause the operation of said place-recording mechanism, and means whereby said place-recording mechanism may be operated independently of said time-recording mechanism.

7. In a signaling system comprising a central station and a series of signal stations, in combination with two recording instruments, one recording a time signal and the 95 other a signal which by its character will designate a particular place, means located at a signal station adapted to send a time signal, connections between said signals whereby the sending of said time signal will 100 cause the sending of said place signal, and means for sending place signals independently of the sending of said time signals, and means whereby said signal boxes must be operated in predetermined order to operate simultaneously said time and place signals.

8. A signaling system comprising a central station and a series of signaling stations, each comprising a time signal mechanism and means whereby time signals can 110 only be given thereby in a predetermined order, and a place signal mechanism, each place signal mechanism being capable of making an individual record, means connecting said time signal mechanism and said place signal mechanism at each station whereby when said time signal is operated said place signal will be simultaneously operated to indicate the place from which said time signal was sent.

9. A signaling system comprising a central station and a series of signaling stations, each comprising a time signal mechanism and means whereby time signals can 125 only be given thereby in a predetermined order and a place signal mechanism, each place signal mechanism being capable of making an individual record, means connecting said time signal mechanism and said place signal mechanism at each station 130

whereby when said time signal is operated said place signal will be simultaneously operated to indicate the place from which said time signal was sent, and means whereby when said place signal is operated independently of said time signal it will make a record differing from its ordinary record when

used with a time signal to indicate such independent operation.
